US0D1048606S

(12) **United States Design Patent** (10) Patent No.: **US D1,048,606 S**
(45) Date of Patent: ** Oct. 22, 2024

(54) **PRESSURE WASHER**

(71) Applicant: **POWERPLAY CORPORATION**, Dorval (CA)

(72) Inventor: **Shawn Kahan**, Dorval (CA)

(73) Assignee: **Powerplay Corporation**, Dorval (CA)

(**) Term: **15 Years**

(21) Appl. No.: **29/858,522**

(22) Filed: **Nov. 1, 2022**

(30) **Foreign Application Priority Data**

Sep. 2, 2022 (CA) ..... CA 215530

(51) LOC (14) Cl. **15-05**

(52) U.S. Cl.

USPC **D32/15**; D3/318; D8/375

(58) **Field of Classification Search**

(57) **CLAIM**

The ornamental design for a pressure washer as shown and described.

DESCRIPTION

FIG. 1 is a front, left perspective view of a pressure washer showing the new design;

FIG. 2 is a front view thereof;

FIG. 3 is a right side view thereof;

FIG. 4 is a rear view thereof;

FIG. 5 is a left side view thereof;

FIG. 6 is a top elevational view thereof; and,

FIG. 7 is a bottom elevational view thereof.

The broken lines in the drawings depict portions of the pressure washer that form no part of the claimed design.

1 Claim, 7 Drawing Sheets
